UNITED STATES PATENT OFFICE

PHILIP CHALFIN AND BENJAMIN CHALFIN, OF PHILADELPHIA, PENNSYLVANIA

METHOD AND APPARATUS FOR REPRODUCING IMAGES AT A DISTANCE

Application filed July 5, 1928. Serial No. 290,358.

Our invention relates to a method and apparatus for producing the likenesses of objects at a distance.

In transmitting and reproducing pictures and particularly in producing likenesses of moving objects at a distance from the transmitting station, it is essential that the receiving apparatus be perfectly synchronized with the transmitting apparatus.

10 The objects of our invention are to provide a method of automatically synchronizing the moving parts of a receiving apparatus with the moving parts of a transmitting apparatus and to provide apparatus for utilizing this 15 method.

This object is attained by dividing the likeness of the subject into a succession of points of light by means of oscillating elements; directing the points of light into a photo-electric cell to cause electric impulses to flow therefrom which vary in intensity in proportion to the lights and shadows of the subject; causing a synchronizing impulse to flow from the photo-electric cell per oscillation of each 20 oscillating element; transmitting the impulses; receiving and amplifying the impulses, directing a beam of light, whose intensity is governed by the impulses received, into oscillating lenses whose oscillations are controlled by the synchronizing impulses; and directing the light from the lenses upon a screen where the likeness is reassembled, due to the oscillations of the lenses.

While our invention may be incorporated 25 in sending and receiving apparatuses of either the wireless or wire connected types and used for the transmission and reception of pictures and the like, it has been shown embodied in a televiser, for use in conjunction with a radio receiving set, and in transmitting apparatus for use in conjunction with a radio broadcasting station.

In the drawings—

Figure 1 is a diagrammatical representation of a radio transmitting apparatus in which an embodiment of our invention has been incorporated,

Figure 2 is a cross-section through the lens elements and the object glass, as indicated by 50 line 2—2 on Figure 1,

Figure 3 an elevation of one of the lens elements shown in Figure 1,

Figure 4 an elevation of the other lens element shown in Figure 1, and

Figure 5 a cross-section through the lens 55 of the element shown in Figure 4,

Figure 6 is a diagrammatical representation of a radio receiving apparatus in which our invention has been incorporated,

Figure 7 an outside elevation of a receiving surface or screen upon which the likeness is projected,

Figure 8 an elevation of one of the lens elements shown in Figure 6,

Figure 9 a sectional plan view taken on 60 line 9—9 on Figure 8,

Figure 10 an elevation of the other lens element shown in Figure 6,

Figure 11 a cross-section through the lens 70 of the element shown in Figure 10, as indicated by lines 11—11 on that figure, and

Figure 12 a diagrammatic drawing of a part of a modified form of receiving apparatus.

Referring first to Figure 1, sounds received 75 by the microphone 1 are amplified by an amplifier 2, modulated by modulator 3 and delivered to the antenna 4 by transmitter 5. As this part of the apparatus is well known and forms no part of our invention, it will not be 80 described in detail.

An object glass 6, preferably consisting of a double convex lens 7 and a meniscus 8, is mounted in the end of a light-tight box 9 which has its interior blackened to prevent 85 reflection of stray rays of light. An oblong oscillating lens element 10, having its axis of oscillation horizontal, is mounted in a light-tight partition 11 in box 9 and an oblong oscillating lens element 12, having its axis of 90 oscillation vertical, mounted in a light-tight partition 13 in box 9 with the axes of oscillation of both lenses in alignment with the axis of the object glass.

Lens element 10 may consist of a lens holder 95 20 (see Figures 2 and 3), having a double concave lens 21 near one end and a double convex lens 22 near the other, and a frame 23 in which the axle 24 of the lens holder is pivoted. The lens holder may be swung in 100

one direction by a magnet 25 which, when energized, will attract an armature 26 secured to axle 24, and in the opposite direction by a second magnet or by a spiral spring 27 having one end secured to the frame and the other end to the axle. In order to overcome any jerk which the magnet might impart and to insure uniform oscillation, a dash pot 28 may be mounted on the frame and have its plunger 29 hinged to an arm 30 secured to the axle.

Lens element 12 may have an oblong double convex lens 31 pivotally mounted in a frame 32 and provided with an armature 33, a magnet 34, a spring 35 and a dash pot 36 which are constructed and function similarly to the corresponding parts of lens element 10. Lens 31 preferably has its side adjacent lens element 10 provided with an opaque covering 37 having a narrow slit 38 on the axis of the lens (see Figure 5). Magnets 25 and 34 may be supplied with energy through an oscillator 39 which is timed to energize magnet 25 once for each complete oscillation of lens holder 20 and to energize magnet 34 once for each complete oscillation of lens 31.

When a subject —A—, either animate or inanimate, is placed before the object glass 30 and illuminated, its image will appear in the plane *a—a* at the front end of lens holder 20 which oscillates to scan the image from top to bottom. This image represents the subject matter to be transmitted and lens holder 20 is wide enough to take in its full width. Flat subject matter, such as pictures and papers, may be placed in plane *a—a* and be scanned directly.

Lens holder 20 is thin and lenses 21 and 22 very narrow so that only a line of light can enter the holder. All divergent rays are reflected by lens 21 against the inside walls of the holder, which are blackened to absorb such rays, and only a very thin line of parallel rays pass into lens 22 from which they issue in a thin line or sheet, representing the variations of light and shade in a line running horizontally across the image.

As lens 31 is vertical and disposed behind lens holder 20, slit 38 will intersect this sheet of light at right angles and allow a beam of light, as wide as the slit and as thick as the sheet of light, to enter the lens. The sheet of light being thin and slit 38 narrow, it follows that but a point or pencil of light, representing a small point on the image, can enter lens 31 at one time. As lens 31 oscillates, succeeding points on the line or sheet of light enter slit 38 and form a continuous stream of light points or a pencil of light whose intensity varies relatively to the lights and shadows on the line on the image covered by the end of the lens holder.

Lens holder 20 oscillates to move its front end from the top to the bottom; or vice-versa,

of the image once for each likeness transmitted and its speed is preferably such that likenesses of moving subjects may be transmitted, e. g. approximately sixteen likenesses per second.

In order to reproduce clearly, each likeness must be divided into fine lines and lens 31 must oscillate to cover the length of lens 22 once for each line. The image is thus disintegrated into lines by lens element 10 and the lines divided into points by lens 31. In effect, the transverse lines projected by lens element 10 are turned by lens 31 and emerge parallel to the axes of the lenses in a pencil of light of varying intensity.

The pencil of light is directed by lens 31 into a photo-electric cell 40, which is connected in an electric circuit, and causes an electric current to flow therefrom which varies in strength in proportion to the intensity of the pencil of light. This current is passed through an amplifier 41 and a modulator 42 to transmitter 5 where it is impressed upon the carrier wave and broadcast in the usual manner.

In order that a receiving apparatus, which will hereafter be referred to as a televiser, may be synchronized with a transmitting station, which will hereafter be referred to as a transmitter, electric impulses are broadcast which will control the oscillations of certain lenses in the televiser. For this purpose, neon tubes 43 and 44 or other suitable sources of light may be placed near photo-electric cell 40 and connected in parallel with magnets 25 and 34 respectively, so that, when a magnet is energized, one of the tubes will be illuminated and cause a strong synchronizing impulse to flow from the photo-electric cell. Thus, a synchronizing impulse is broadcast at the beginning of each oscillation of each lens element.

Referring now to Figure 6, the impulses, broadcast by the apparatus shown in Figure 1 and representing both sound and light, are picked up by the radio receiver 50. The impulses representing sound pass through a filter 51 and are converted into sound waves by a speaker 52 in the usual manner.

The impulses representing light rays pass through a filter 53 to the televiser which has an amplifier 54 consisting of one or more stages of resistance coupled amplification. The plate of the last tube 55 of amplifier 54 is connected by a wire 56 to one terminal of a light valve 57 whose other terminal is connected by a wire 58 to a source of energy 59 which supplies amplifier 54 with power; the output of the amplifier being controlled by a rheostat 60 connected in the filament circuit.

A lamp 61 is connected by wires 62 and 63 to a suitable source of power, such as a lighting circuit, and the flow of current through the lamp is regulated by a rheostat 64. A reflector 65, placed behind lamp 61, directs

light from this lamp into a lens 66 which concentrates the light into light valve 57.

The light valve consists of a pair of light polarizing devices 67 and 68, having their planes of polarization at right angles to each other and shown as being Nicol prisms, and a device 69 for rotating a polarized beam of light, which is shown as being a Karolus cell. The beam of light projected by lens 66 will be polarized by device 67, pass through 10 the Karolus cell and be blocked by device 68, due to the relation of device 67 to device 68.

When energized by the output of amplifier 54, the Karolus cell will produce a "Kerr effect" or rotate the polarized beam of light 15 in proportion to the strength of the electric impulse received. A pencil of light, varying in intensity as the intensity of the pencil of light directed into the photo-electric cell in the transmitter varies, is thus permitted to pass through device 68. A lens 70, mounted for oscillation in the path of this pencil, directs it into an oblong oscillating lens 71 which directs it upon a screen or receiving 20 surface 72 mounted at the focus of lens 71 and adjustable toward and from the lens by an adjusting screw 73. The televiser should be installed in a light-tight box and the light valve and lenses set into light-tight partitions. Receiving surface 72 may be a 25 translucent screen, such as a ground glass plate, and be adjustably mounted in the end of the light-tight box.

If the surface 72 is in a vertical plane, lens 30 71 will have its axis of oscillation in a horizontal plane and sweep its focus, in unison with lens holder 20 in the transmitter, vertically over surface 72 once for each likeness reproduced, while lens 70 will have its axis 35 of oscillation in a vertical plane and, in unison with lens element 12 in the transmitter, sweep its focus horizontally across lens 71.

Photo-electric cells 74 and 75, shielded 40 from light reflected from surface 72 by shields 76 and 77, are mounted adjacent surface 72 and connected to devices 78 and 79, such as 45 relays or amplifiers, for increasing the output of the cells. When magnet 25 is energized, the synchronizing impulse broadcast, due to the illumination of neon tube 43, is 50 received and causes a strong beam of light to pass through the light valve. This beam is directed into cell 74 by the lenses, causing a current to flow which is amplified by device 78 and directed to a magnet 80 for oscillating 55 lens 71. In like manner, when a strong impulse is broadcast due to the energization of magnet 34, a strong beam of light will be directed into cell 75 and cause a current to flow which is amplified by device 79 and directed to a magnet 81 for oscillating lens 70.

In order to oscillate the lenses with one magnet each, as shown in Figure 6, the lens elements shown in Figures 8 to 11 may be 60 employed. Lens 70 is shown secured in a

mounting 86 which is pivoted between two pointed screws 87 threaded through the top and bottom of a frame 88 so that the lens may oscillate with a minimum of friction. Magnet 81 is secured to the frame and adapted to 70 attract an armature 89 on mounting 86. A spiral spring 90, having one end secured to the mounting and the other to a pin 91 in the frame, tends to keep lens 70 oscillating when it is once set in motion; magnet 81 adding 75 the necessary impetus once during each complete oscillation.

In order to overcome any jerk which the magnet might impart to the lens and to make 80 the rate of movement practically uniform throughout each oscillation, a small dash pot 92 may be secured to the frame and its plunger 93 hinged to an arm 94 on mounting 86 opposite armature 89.

Lens 71 may be mounted on an axle 95 pivoted between pointed screws 96 threaded through the sides of a frame 97 and magnet 80 secured to the side of the frame with its armature 98 fixed on axle 95. A spiral spring 99 may have one end secured to a pin 100 in 90 the frame and its other end to the axle. A dash pot 101 may be secured to the frame and have its plunger 102 hinged to an arm 103 fixed on the axle. The magnet, spring and dash-pot function similarly to those which 95 control the oscillation of lens 70.

The modified arrangement shown in Figure 12 differs from that shown in Figure 6 only in that the lenses are oscillated by two magnets each and a solenoid employed in the 100 light valve instead of a Karolus cell.

The light valve 110 consists of a solenoid 111 disposed between light polarizing devices 67 and 68 and connected to amplifier 54 by wires 56 and 58. When amplifier 54 sends impulses through solenoid 111, a magnetic field will be set up which will rotate a polarized beam of light in proportion to the strength of the impulses, thus functioning in the same manner as the Karolus cell previously described and permitting a beam of light of varying intensity to enter lens 70.

No details of the lens mountings have been shown, as the mountings shown in Figures 8 and 10 may be modified and provided with 110 two magnets each and with one or two armatures. Lens 70 has been shown with an armature 112 substituted for arm 94, a magnet 113 provided for this armature and lens 71 provided with a magnet 114 placed on the opposite side of armature 98 from magnet 80.

With this arrangement, two magnets are employed for oscillating each lens element in the transmitting apparatus and photo-electric cells 115, 116, 117 and 118 placed around surface 72. Magnets 81 and 113 are energized through the agencies of cells 115 and 116 which are connected to the magnets through relays or amplifiers 119 and 120, respectively. Magnets 80 and 114 are energized through 120 125 130

the agencies of cells 117 and 118 which are connected to the magnets through the relays or amplifiers 122 and 123, respectively.

Assuming that it is desired to broadcast a speech and the likeness of the speaker, he will be placed before the object glass, well illuminated, the microphone positioned to catch the sound of his voice, and the transmitter put into operation.

When the televistor shown in Figure 6 is not in operation, the spiral springs will direct lenses 70 and 71 toward photo-electric cells 75 and 74. When the televistor is put into operation, lens 70 will start to oscillate in unison with lens element 12, due to the illumination of neon tube 44 each time magnet 34 is energized but lens 71 will not start to oscillate until a synchronizing impulse has been sent out due to the energization of magnet 25. As soon as this impulse is received, lens 71 will oscillate in unison with lens elements 10 and 70 with lens element 12, thus synchronizing the televistor with the transmitter.

The light from lamp 61 is allowed to pass through the light valve in proportion to the strength of the impulses which are in proportion to the intensity of the light reflected from the subject. Thus the likeness of the speaker is reproduced point by point upon screen 72 in exactly the same manner and at exactly the same time that the image of the speaker is disintegrated, point by point by lens elements 10 and 12.

It is apparent that the size of the image on screen 72 may be increased or decreased by moving the screen toward or from lens 71 and that the brightness of the image may be regulated by increasing or decreasing the light from lamp 61, as by regulating the current input with rheostat 64 or substituting a lamp of different candle power.

The embodiment of the invention as set forth above may be varied in numerous particulars and various substitutions may be made therein within the scope of the invention as hereinbefore set forth and herein-after claimed.

We claim:

1. An apparatus for transmitting the likeness of subject matter including oscillating means for scanning the subject matter vertically and disintegrating the likeness into lines of light, oscillating means for disintegrating the lines of light into a series of points of light and directing the points of light into a photo-electric cell to cause light regulated electric impulses to flow therefrom, means acting on the photo-electric cell to cause synchronizing electric impulses to flow therefrom along with the light regulated impulses, and means for transmitting the impulses.

2. An apparatus for transmitting the likeness of subject matter including an oblong

lens holder, means for oscillating the lens holder to move one of its ends over the space occupied by the subject matter, said lens holder embodying means to disintegrate light into lines, an oblong oscillating lens having its axis of oscillation at right angles to the axis of oscillation of the lens holder and within the field of said lines, means for oscillating the lens and lens holder, a photo-electric cell mounted in the focus of the lens, means for illuminating the subject matter whereby light reflected therefrom will be directed into the photo-electric cell by the lens and cause electric impulses to flow from the cell, means for amplifying the impulses, and means for transmitting the impulses.

3. An apparatus for transmitting the likeness of subject matter including a lens holder, means for oscillating the lens holder to move one of its ends over the space occupied by the subject matter, an oblong oscillating lens having its axis of oscillation at right angles to the axis of oscillation of the lens holder, means for oscillating the lens and lens holder, a photo-electric cell mounted in the focus of the lens, means for illuminating the subject matter whereby light reflected therefrom will be directed into the photo-electric cell by the lens and cause electric impulses to flow from the cell, means for causing an additional impulse to flow from the photo-electric cell per oscillation of the lens holder, means for causing an additional impulse to flow from the photo-electric cell per oscillation of the lens, means for amplifying the impulses, and means for transmitting the impulses.

4. A televistor, for reproducing likenesses transmitted from a sending station as electric impulses, including means for receiving the impulses, an amplifier connected to the receiving means, a light valve connected to the amplifier, a lamp connected to a source of power, means for directing a beam of light from the lamp into the light valve, an oscillating lens aligned with the light valve, an oblong oscillating lens mounted in alignment with the first lens, a receiving surface mounted at the focus of the oblong lens, means for oscillating the first lens in one direction, and means for oscillating the oblong lens in the other direction.

5. A televistor, for reproducing likenesses transmitted from a sending station as electric impulses, including means for receiving the impulses, an amplifier connected to the receiving means, a light valve connected to the amplifier, a lamp connected to a source of power, means for directing a beam of light from the lamp into the light valve, an oscillating lens aligned with the light valve, an oblong oscillating lens aligned with the first lens with its axis of oscillation at right angles to that of the first lens, a receiving surface mounted at the focus of the oblong lens, photo-electric cells adjacent the receiving

- surface, and magnets for oscillating the lenses energized through the agency of currents emanating from the photo-electric cells.
6. A televisor, for reproducing likenesses transmitted from a sending station as electric impulses, including means for receiving the impulses, an amplifier connected to the receiving means, a light valve connected to the amplifier and consisting of a device for rotating a polarized beam of light disposed between a pair of light polarizing devices, a lamp connected to a source of power, means for directing a beam of light from the lamp into the light valve, an oscillating lens aligned with the light valve, an oblong oscillating lens aligned with the first lens, a receiving surface mounted at the focus of the oblong lens, means for oscillating the first lens in one direction, and means for oscillating the oblong lens in the other direction.
7. An apparatus for transmitting the likeness of a subject consisting of means for directing rays of light reflected from the subject through members having narrow elongated openings extending at right angles to each other and oscillatable about axes parallel to said openings, into a photo-electric cell, connected into an electric circuit, and means for transmitting the electric impulses emanating from the cell under the influence of the rays of light.
8. The method of transmitting the likeness of a subject matter consisting of scanning the subject matter to divide the light reflected therefrom into oscillating horizontal lines, scanning the plane of the lines to divide them into a succession of points forming a pencil of light, oscillating in a vertical plane directing the pencil of light in impulses into a photo-electric cell which is connected into an electric circuit directing further light into the photo-electric cell together with that from the impulses incident to the scanning operation, and transmitting the impulses flowing from the cell.
9. The method of transmitting the likeness of subject matter consisting in oscillating an aperture element, which is as wide as the subject matter, in a horizontal plane in close proximity to the subject matter to divide the reflection therefrom into lines of light through the aperture, oscillating element in a vertical plane to intercept the lines of light and divide them into a succession of points forming a pencil of light, directing the pencil of light together with the rays from another source into a photo-electric cell connected into an electric current transmitting the impulses flowing from the cell.
10. The method of synchronizing a televisor having oscillating elements actuated by magnets, with a sending station, having oscillating elements consisting in transmitting an electrical impulse per oscillation, connecting each magnet to a source of energy controlled by a photo-electric cell, receiving the impulses transmitted, converting the impulses into rays of light, and directing the rays of light into the photo-electric cells.
11. The method of synchronizing an oscillating element in a receiving apparatus with an oscillating element in a transmitting apparatus consisting in providing the transmitting apparatus with a photo-electric cell and a lamp, connecting the cell into an electric circuit, flashing light from the lamp into the cell at each oscillation of the oscillating element in the transmitter to cause electric impulses to flow from the cell, transmitting the impulses; providing the receiving apparatus with a magnet for actuating the oscillating element, providing the magnet with energy controlled by a photo-electric cell, directing a beam of light into a light valve, receiving the impulses, amplifying the impulses and directing them to the light valve for causing light to issue therefrom and enter the photo-electric cell.
12. An apparatus for transmitting the likeness of subject matter including means for scanning the subject matter vertically and disintegrating the likeness into lines of light, means for disintegrating the lines of light into a series of points of light and directing the points of light into a photo-electric cell to cause light regulated electric impulses to flow therefrom, means acting on the photo-electric cell to cause synchronizing electric impulses to flow therefrom along with light regulated impulses, and means for transmitting the impulses, said synchronizing impulses being caused incident to the operation of both of the disintegrating means.
13. An apparatus for transmitting likeness of subject matter including means for scanning and disintegrating the image of the subject matter into a beam of light, electro-magnetic means for operating said means to play the beam of light upon a photo-electric tube, means operable by the electro-magnetic means for playing additional light impulses on said photo-electric tube, and means for transmitting said impulses to a receiving station.
14. An apparatus for transmitting likeness of subject matter including a member operable for scanning the subject matter and a member for disintegrating the result of the scanning member into a pencil of light, electro-magnets for oscillating said members, a photo-electric cell into which the pencil of light is directed, means for directing additional light impulses into said cell controlled by the actuation of each of said electro-magnets, and means for transmitting the impulses from the cell to a receiving station.
15. Apparatus for reproducing likenesses of subject matter at a distance including a photo-electric cell, scanning mechanism adapted to disintegrate a likeness and play

the same in a pencil of light upon said cell in impulses varying with the light and shadows of the image, means for transmitting impulses from said cell to a receiving station, means at the receiving station for 5 directing a beam of light toward a receiving surface, obstructing means for intercepting said beam, and means operable under the influence of said impulses for rotating said beam so as to cause it to pass said obstructing means.

16. Apparatus for reproducing a likeness of subject matter at a distance, said apparatus including a transmitter and a televiser, the transmitter including a photo-electric cell, scanning means for disintegrating the light from the subject matter into light impulses and directing said impulses into said cell, electro-magnetic means for oscillating 15 said scanning means, and light producing means operable incident to the operation of the electro-magnetic means for directing secondary impulses into said cell, means for transmitting the impulses from said cell, 20 means connected with the televiser for receiving said impulses, said televiser including means for directing a beam of light toward a receiving surface, means influenced by said received impulses for varying the 25 intensity of said beam oscillatable means for spreading said beam on the receiving surface, and means controlled by said secondary 30 impulses for causing the oscillation of said oscillatable means.

17. Apparatus for reproducing likeness 35 at a distance comprising a transmitter and a televiser, the transmitter including spaced members each adapted to refract light in one dimension only and positioned with their major axes at right angles, means to oscillate the members in synchronism, a member 40 adapted to transmit variations of light impulses as variations of electrical impulses, said transmitter being positioned to intercept light rays from one of said refractors, said televiser including a light valve whose 45 transmitting capacity is variable by the said electrical impulses, a light receiving surface, a source of light directed toward said surface through said valve, and means to direct the transmitted light in synchronism with the oscillations of the refractors of the transmitter.

18. In apparatus for reproducing likeness 55 at a distance, spaced members adapted to refract light in one dimension only, said refractors being mounted with their major axes at right angles, means to oscillate one refractor to scan an entire image by progressive linear areas and project the lines of 60 light upon the other refractor, a light responsive unit, and means to oscillate the second refractor in synchronism with the first refractor to project pencils of light upon said 65 unit.

19. In apparatus for reproducing likeness 70 at a distance, spaced interacting refractors adapted to refract light in one dimension only and mounted with their major axes at right angles, and means to oscillate the refractors upon their major axes synchronously.

20. A radio television comprising means 75 for transmitting impulses generated by the objects scanned, means to produce and transmit impulses supplemental to said scanning impulses, means to receive said scanning impulses, means to independently receive said supplemental impulses, means to employ said supplemental impulses to control the receiving means in synchronism with the transmitting impulses and means at the receiver to produce return impulses for controlling the transmitting impulses in synchronism with the receiving means.

21. A radio television comprising means 80 for transmitting impulses generated by the objects scanned, means to produce and transmit impulses supplemental to said scanning impulses, means to receive said scanning impulses, means to independently receive said supplemental impulses, means to employ said supplemental impulses to maintain the receiving means in synchronism with the transmitting impulses and means at the receiver to produce return impulses for maintaining the transmitting impulses in synchronism with the receiving means.

In testimony whereof we have signed our names to this specification.

PHILIP CHALFIN.
